UNITED STATES PATENT OFFICE.

FREDERICK HARVEY RAPLEY, OF CHICAGO, ILLINOIS, ASSIGNOR TO THE FOX SOLID PRESSED STEEL COMPANY, OF SAME PLACE.

UNDERFRAME FOR CARS.

SPECIFICATION forming part of Letters Patent No. 585,405, dated June 29, 1897.

Application filed April 10, 1896. Serial No. 586,911. (No model.)

To all whom it may concern:

Be it known that I, FREDERICK HARVEY RAPLEY, of Chicago, Cook county, Illinois, have invented new and useful Improvements 5 in Underframes for Cars, of which the following is a full and complete description.

This invention relates to railway-cars; and it consists in an improved form of steel underframe or that portion of a car upon which 10 the flooring is laid and which supports the body of the car upon its trucks.

My improved form of underframe combines maximum strength with minimum weight of metal, together with novel and desirable 15 methods of securing together the various parts thereof.

My improvements are fully illustrated in the accompanying drawings, in which—

Figure 1 represents a plan of the underframe with part of the draft-gear; Fig. 2, an elevation of the same, showing portions of the truck and car brace-timbers in dotted lines. Fig. 3 is a part sectional plan of the underframe; Fig. 4, a sectional elevation of 25 the same. Fig. 5 is a half end elevation of the frame; and Fig. 6 is a sectional elevation on the line $x-x$, Fig. 3.

The longitudinal sills a^4 , a^5 , and F of the improved underframe are preferably constructed of rolled steel and the end sills a' of pressed steel. The body-bolster beams G and the transverse sills a^2 a^3 are preferably formed of pressed steel. The mode of securing the draft-gear to the central longitudinal sills F is illustrated in Figs. 3 and 4, the cheek-plates or draft-sills $f-f$ being riveted thereto. The transverse sills a^2 a^3 are provided with longitudinal flanges b' , whereby they are secured to the longitudinal sills. The truck-sills are 35 each composed of two parts a^2 , secured to the side sills by their flanges and by the horizontal plates B B, riveted thereto, and to the central longitudinal sill F by the horizontal plates b^2 . The corners C of the underframe are 40 secured together and to the ends of the bolster-beams by special gussets g^2 . The central sills are secured at their ends by angle-plates f^2 , which are bolted through the buffer-beams 45

and also riveted to the sides of the central longitudinal sills, as at f^3 . Vertical bolts g^4 50 are also used to secure the end plates to the buffer-beams. The intermediate longitudinal sills are flanged and riveted to the end sills and bolster-beam G, as at g' . The base and center plates J, truck-bolster H, draw-bar 55 guide g^3 , and side bearing K are of ordinary construction.

The partial views of the various parts given in the drawings herewith illustrate those parts not shown, which are simply duplicates 60 of those represented.

In other designs for metal underframes for cars with which I am acquainted diagonal braces have been used for securing together the various parts of the frame and imparting 65 additional strength and rigidity to it. The gusset-plates of my improved frame, however, constitute a more simple and effective way of attaining these ends, are more readily secured to the frame, and occupy less space than do 70 other similar devices.

In the practice of my invention I am not of course limited to the use of bolts or rivets in securing together the various parts of the underframe, nor as to any particular type of 75 car, as my improved frame may be applied to any of the several classes of railway-cars in common use. It is, however, specially adapted to iron or steel cars of any well-known type.

Having thus described my invention, I 80 claim—

In an underframe for cars, the combination of the end sills a' , the transverse sills a^2 a^3 , the corner gusset-plates g^2 , the intermediate longitudinal sills a^5 , provided with flanged 85 ends g' for securing same to the end and transverse sills, the horizontal octagonal plates b^2 b^4 , and the hexagonal side plates B B, substantially as specified.

In testimony whereof I have signed my 90 name to this specification in the presence of two subscribing witnesses.

FREDERICK HARVEY RAPLEY.
